UNITED STATES PATENT OFFICE.

JOHN W. GOODERHAM, OF YONKERS, NEW YORK, ASSIGNOR TO WESTERN ELECTRIC COMPANY, INCORPORATED, OF NEW YORK, N. Y., A CORPORATION OF NEW YORK.

REGISTERING SYSTEM.

Application filed June 12, 1922. Serial No. 567,539.

To all whom it may concern:

Be it known that I, JOHN W. GOODERHAM, a citizen of the United States, residing at Yonkers, in the county of Westchester, State of New York, have invented certain new and useful Improvements in Registering Systems, of which the following is a full, clear, concise, and exact description.

This invention relates to automatic telephone exchange systems and more particularly to systems employing automatic switches in which such switches are controlled by means of a sender located at a central office.

It is the object of this invention to provide an improved means for transferring registrations from one register to another.

It is more specifically the object of this invention to provide an improvement over a system of the type shown and described in an application, Serial No. 568,747, filed June 16, 1922, by E. H. Clark.

In the system disclosed in the Clark application, a plurality of multiple contact relays are arranged on a coordinate basis and are energized under the control of a primary registering device. They are subsequently utilized in transferring a registration from such primary registering device to some other registering device.

A feature of the present invention is an organization of circuits such that these relays may be commonly available to the primary registers instead of individual thereto.

A further feature of the invention is the use of an allotter switch to control the effective association of said common relays with a particular primary registering device.

Other features of the invention result from the arrangements of the circuits which control the setting of the registers and will be clearly apparent from the detailed description which follows.

The invention has been shown applied to a full automatic system of the type shown in Patent No. 1,395,977, issued November 1, 1921, to F. A. Stearn and F. J. Scudder. The invention is, however, obviously capable of a wide range of usage and is therefore not to be limited to the specific embodiment shown.

In the drawing, the various figures show so much of a telephone exchange system as

is necessary to the understanding of the invention. Fig. 1 shows a calling subscriber's substation and switches by means of which a connection may be extended to a called substation, these switches being diagrammatically indicated, as is a sender selector. The lower portion of Fig. 1 shows a register sender provided with a plurality of step-by-step primary registering devices. Fig. 2 shows transfer relays which are commonly available to a group of senders and other relays also individual to each sender of the group whereby the transfer relays may be controlled. The lower left-hand portion of this figure shows an allotter switch which determines in what order the registrations set up on the senders of its group shall become effective. Fig. 3 shows a set of register relays which may be used to control the selective operations of the switches diagrammatically indicated in Fig. 1.

A general description of the system will first be given in order that the detailed description which follows may be more readily understood.

The general operation of the system is substantially similar to that described in the above mentioned patent to F. A. Stearn and F. J. Scudder, No. 1,395,977. When the calling subscriber removes his receiver from the switchhook, a line switch is put into operation to select a trunk leading to an idle district selector. The seizure of such trunk puts into operation a sender selector which associates an idle sender with the selected trunk circuit. Each sender is provided with a plurality of step-by-step primary registering devices. These registering devices may be of any desired character, but are preferably of the type shown and described in Patent No. 1,472,465, issued October 30, 1923, to O. F. Forsberg and R. M. De Vignier. A progression controlling switch is utilized to direct the successive series of impulses to the proper registering devices. Assuming that the system is to serve a large exchange area, it may well be that 500 offices will have to be served. By utilizing the first three registers to record the office designation, one thousand office combinations may be obtained. In the present disclosure, it will be assumed that each of the first three registers has only eight

effective registering positions, thus providing for a total capacity of 512 offices.

All of the senders of an exchange office are divided into groups. A set of multi-contact relays is associated with each group of senders, as is an allotter switch. The multi-contact relays may be of any desired mechanical construction, but are preferably of the type shown and described in an application, Serial No. 482,106, filed July 2, 1921, in the name of O. F. Forsberg.

It will be assumed that in order to obtain connection to a desired office, the calling subscriber must dial three times. Three primary step-by-step registering devices are therefore provided to receive these series of impulses. The register which receives the first series of impulses will be herein-after referred to as the A register, the register which receives the second series of impulses will be referred to as the B register, and the register which receives the third series of impulses will be referred to as the C register. A set of eight multi-contact relays is commonly available to all the C registers of a particular group of senders. Each of these relays is provided with 64 contacts. It will be assumed that the C register has eight effective positions. A different one of the multi-contact relays, just referred to, will be actuated in each of the effective positions of an allotted C register.

A set of eight multi-contact relays are commonly available to all the B registers of a sender group, as in the case of the C registers. These relays may be associated with a particular B register under the control of an allotter. These multi-contact relays each have eight contacts thus providing 64 outlets as a result of the eight possible settings of the B register and the eight possible settings of the A register. A different one of these eight relays is operated in each effective position of a B register. It will thus be obvious that by suitably coordinating the A, B and C registers and a set of relays to which such registers have been allotted, potential may be directed to any one of 512 outlets. Eight outlets from the A register are multiplied to the common cross wires of the eight relays associated with the B register and, in accordance with which one of the relays associated with the B register is energized, any one of 64 outlets may be supplied with potential. These 64 outlets are multiplied to the eight relays associated with the C register and, in accordance with which one of these relays is energized, potential may be supplied to any one of 512 outlets.

There is associated with each group of senders, a multi-contact relay organization comprising 512 relays, each having twenty contacts. After the primary step-by-step

registers have been positioned, potential is supplied to the desired outlet selected by the primary registers of the sender under the control of an allotter which prevents interference between senders of the same group. One of the 512 control relays is thereupon energized and places the proper combination of potentials on the cross wires of the transfer relay frame.

There is provided for each sender a relay having twenty contacts a portion only of which are shown. Each of these relays has access to the common multiple cross wires which have been provided with a suitable combination of potentials under the control of the registers. Upon the energization of the multi-contact relay which is individual to a particular sender, the desired combination of potentials is placed on nineteen conductors extending to the register relays of Fig. 3, which are individual to the corresponding sender. These relays, upon energization, are locked up and are then utilized to control the selective operations of the switches which establish the connection in a well-known manner.

Summing up, the organization is such that by means of a set of primary registering devices comprising A, B and C registers and the common relays which cooperate with an allotted register set, one of 512 relays which are common to the senders of a group is energized under the control of the allotter. The particular one of 512 relays energized places potential on the particular ones of the cross wires which will accomplish the energization of the desired ones of the register relays of Fig. 3. After the registration is placed on the common cross wires of the transfer relay structure, the registration is directed to the register relays of the particular sender then allotted by means of a relay individual to such sender. It is obvious that by combinations of the nineteen register relays of Fig. 3, more than 512 office designations may be recorded so that it will not be necessary to use all possible combinations of the register relays. It is also obvious that by changing the combination of potentials controlled by any one of the 512 relays which function in connection with the transfer frame that the change in routing thus accomplished will be automatically effective on all the senders of a group. If the terminals of the corresponding register relays of all register relays of all groups are multiplied and brought to a distributing frame, it is obvious that a change of routing may be accomplished by simply changing connections at such distributing frame, and that such change will then be effective on all the senders of the exchange. The advantage in the way of common cross connections which is incident to the use of a translator switch is thus retained in the

present system. It is believed that the operation of the system will be fully understood in view of the following detailed description.

5 When the subscriber at substation 1 desires to initiate a call, he will remove his receiver from the switchhook, causing the operation of line switch 2 to connect the substation line to a trunk leading to an idle 10 district selector. The seizure of such trunk causes the operation of a sender selector, generally indicated at 3, which causes an idle sender to be associated with the trunk circuit which has been taken for use. The operation 15 of the line switch 2, and the sender selector 3 are well known, and it is believed that their operation will be understood without further description. The previously mentioned Patent No. 1,395,977, shows suitable circuits for accomplishing this operation.

It will be assumed that the register sender shown in Figs. 1, 2 and 3 is associated with the calling subscriber's line. As soon as 25 such association is completed, line relay 4 is energized over the line loop of the calling substation by way of the wipers and contacts of the sender selector 3 and line switch 2. The energization of line relay 4 causes the 30 energization of slow release relay 5. The energization of relay 5 causes the energization of stepping magnet 6 of the control switch over a circuit extending by way of the right hand armature and back contact 35 of slow release relay 7 and the right hand armature and front contact of relay 5 to ground. Stepping magnet 6 is energized and withdraws the stepping pawl into engagement with a new tooth of the ratchet 40 so that upon deenergization, the control switch may be advanced.

The calling subscriber now operates his substation dial to transmit the first series of impulses. The first deenergization of line 45 relay 4 causes the energization of slow release relay 7, which upon energization causes the deenergization of magnet 6 so that the control switch advances its wipers into engagement with their first contacts. A circuit 50 is then completed from grounded battery, stepping magnet 8, which controls the A register switch, wiper 9 and its first contact, left hand armature and front contact of relay 5, armature and back contact of relay 4, to ground. Magnet 8 is energized but does not 55 advance the A register until relay 4 is again energized upon the completion of the first impulse. Relays 5 and 7 being slow to release remain energized during the sending 60 of the first series of impulses. When the series of impulses is completed, the continued energization of relay 4 for a relatively long period causes the deenergization of relay 7. Control switch magnet 6 is again 65 energized so that upon the start of the sending of the second series of impulses the control switch is advanced into its second position to bring stepping magnet 10 of the B register under the control of line relay 4. The B register is positioned in the well known manner. Upon the start of the third series of impulses the control switch places stepping magnet 11 of the C register under the control of the line relay 4. After this series of impulses has been transmitted the subscriber sends the digits of the wanted number. Since the present invention is not concerned with the method of recording this registration, it will be assumed that they are received in a manner corresponding to that shown in the previously mentioned Patent No. 1,395,977.

As soon as the C register is completely positioned, as is indicated by the deenergization of slow release relay 7, a circuit is completed from grounded battery, winding of start relay 12, armature and back contact of relay 13, right hand armature and back contact of relay 7, C register brush 14 and some off normal contact to ground. Relay 12 is energized in this circuit and completes a circuit by way of its outer armature and front contact, conductor 15, which is multiplied to the corresponding contacts of relays 12 of other senders of the same group, left hand armature and back contact of test relay 16, armature and back contact and winding of allotter stepping magnet 17, to grounded battery. Stepping magnet 17 is energized and causes the energization of slow release relay 18. Magnet 17 interrupts its own circuit to cause the advance of the allotter switch into engagement with terminals assigned to the particular sender on which the start relay is actuated. When the wipers of the allotter switch engage such terminals, a circuit is completed from grounded battery, winding of test relay 16, allotter brush 18 and its second contact, which it will be assumed is the contact assigned to the sender shown in Fig. 1, conductor 19, middle armature and front contact of relay 12, to ground. Test relay 16 is energized and opens the circuit of stepping magnet 17, thus bringing the allotter to rest. The continued deenergization of stepping magnet 17 allows slow release magnet 18 to deenergize and complete a circuit from ground, through its armature and back contact, right hand armature and front contact of relay 16, allotter brush 20 and its second contact, conductor 21, winding of relay 22, to grounded battery. Relay 22 is energized, and at its left hand armature completes a circuit to cause the energization of relay 13, which locks to ground at C register brush 14.

It will be assumed that the A register is in position 3, the B register in position 2, and the C register in position 2. The energization of relay 22, therefore, completes a

circuit from grounded battery, winding of relay 23, outer right hand armature and front contact of relay 22, A register brush 24, and its third contact, conductor 25, and thence to the grid wire 26 of the relay structure associated with the B register. At the same time, a circuit is completed from grounded battery, winding of relay 23, middle right hand armature and front contact of relay 22, B register brush 27 and its second contact, conductor 28, winding of relay magnet 29, to ground. Magnet 29 is energized and extends battery supply from grid wire 26 to conductor 30. It is to be understood that there are eight grid wires common to the eight relays corresponding to relay 29. For the sake of simplifying the disclosure they have not all been shown.

The energization of relay 22 also completes a circuit from grounded battery, winding of relay 23, inner right hand armature and front contact of relay 22, C register brush 31 and its second contact, conductor 32; winding of relay magnet 33, to ground. Relay 33 is energized and connects its contacts to the common grid wires which are associated with the B register relays. It is to be understood that there are 64 of these common grid wires, a portion only of these wires being shown to avoid needless extension of the drawings. The energization of relay 33 extends conductor 30 to conductor 35 by way of grid wire 36. The battery potential supplied to conductor 35 causes the energization of relay magnet 37, which is energized, and supplies battery potential to desired ones of the cross wires which constitute the grid of the transfer relay structure. It is obvious that the relay magnet 37 has been selected out of the 512 similar magnets as a result of the coordination of the A, B and C registers and the multi-contact relays which have been associated with them. It is also obvious that no other relays corresponding to 37 can be energized at this time since they can only be energized under the control of a relay corresponding to relay 22. Since relay 22 is energized under the control of an allotter, it is obvious that even though the senders which are indicated by the dotted rectangles to the left of Figs. 1 and 2 have their registers positioned, such positioning is without effect on the transfer structure since the allotter can assign only one sender at a time. Furthermore, the fact that the registers associated with other senders may be positioned, can have no effect on the groups of relays containing relays 29 and 33 since the energization of these relays is controlled by relay 22 and the relay 22 of only one sender can be energized at a time since it is under the direct control of the allotter. It should be noted that the conductors 25, 28, 32, etc., are indicated as being

multiplied to corresponding points on the registers associated with other senders in the same allotter group.

It is to be observed that the circuits just described, which were completed through the winding of relay 23, cause the energization of this relay. The energization of relay 23 causes the energization of relay magnet 38 over an obvious circuit. Relay 38 is individual to the sender under allotment and the energization of this relay causes the registration set up on the grid wires to be transferred to the register relays of Fig. 3.

It is believed that the method of transferring the registration to the register relays of Fig. 3 will readily be understood. The energization of relay magnet 37 places battery potential on the common grid wires 39, 40, 41, 42, 43, 44 and 45, indicative of the dialed office code No. 322, and the energization of relay magnet 38, which is individual to the particular sender under allotment, causes this battery potential to be supplied to conductors 46, 47, 48, 49, 50, 51 and 52, respectively. If any other relay had been operated, say 80, battery would be supplied to grid wires 40, 62, 63 and 64 and transferred to conductors 47, 65, 66 and 27. Relay 80, it will be noted, will be energized in response to the registration of No. 422. For each number registered a different relay of the 37 group will be operated and battery potential will be supplied to the proper conductors in accordance therewith. It is to be understood that each of the conductors numbered from 46 to 52, inclusive, is permanently connected to the right-hand winding of one of the register relays of Fig. 3. There are as many of these conductors as there are register relays in Fig. 3. All of the conductors have not been shown in order to avoid needless duplication. The actual connection from the conductors to the relays is not shown, since it is believed that the arrangement of this part of the system may readily be understood without showing the actual conductors. The conductors have been shown as terminating in the cable 53 which is fanned out to the various rows of relays at points 54, 55, 56, 57 and 58. Nineteen register relays have been shown in Fig. 3 and it will therefore be assumed that 19 conductors extend to the contacts of relay 38 and that these 19 contacts are selectively supplied with potential by means of the 19 grid wires corresponding to wires 39 to 45, inclusive, which are in turn selectively supplied with potential in accordance with which one of the relays corresponding to relay 37 is energized. By selectively supplying potential to the set of 19 conductors of which conductors 46 to 52 are a part, the 19 register relays of Fig. 3 are selectively energized by means of a circuit from battery to

ground through their right-hand windings. These relays, upon energization, lock up through their left-hand windings. The locking battery supply is not shown, but it is supplied in the same manner as it is supplied in the previously mentioned Patent No. 1,395,977. It should be observed that the register relays of Fig. 3 correspond exactly and bear the same numerical designation as the register relays of Fig. 10 of the patent just mentioned. The controlling leads by means of which these relays control the selective operations of the district and office switches and also by means of which they control the determination of the class of call, are identical with those shown in the above patent. It is, therefore, believed that no further description is needed as to the method in which these register relays control counting relays to govern the switches indicated in Fig. 1, since a complete description of an identical operation occurs in the patent.

While this registration is being transferred to the relays of Fig. 3, the calling subscriber has been sending in series of impulses in accordance with the numerical designation of the wanted line. These impulses are received on registers as described in the mentioned Patent No. 1,395,977, and are later utilized to control incoming and final selector switches or else to control a call indicator at an operator's position. Since this part of the operation of the system is in every way similar to that shown and described in such patent, it is believed that description of this part of the operation is unnecessary in the present application.

It should be observed that the energization of relay magnet 38 selectively supplies battery simultaneously to the relays of Fig. 3 and that no more time is required for this transfer than would be required for the energization of a single relay.

The energization of relay magnet 38, which causes the transfer of the registrations from the relays of Fig. 2 to those of Fig. 3, also causes the immediate advance of the allotter switch. The advance of the allotter switch is accomplished due to the completion of a circuit from ground, the upper cross wire of the grid served by the relays corresponding to relay 38, the inner contact of relay 38, conductor 59, allotter brush 60 and its second contact, armature and back contact and winding of allotter stepping magnet 17 to grounded battery. The allotter switch advances its wipers one step thus causing the release of relays 22 and 12. The circuit of relay 22 is opened by allotter brush 61. The release of relay 22 causes the deenergization of relay 23 which allows relay magnet 38 to be deenergized. Deenergization of relay 22 also

causes the release of relay magnets 29 and 33 as well as relay magnet 37.

It should be noted that relay 22, upon energization, causes the energization of relay 13 which is locked up to ground at an off-normal contact served by C register brush 14. The energization of relay 13 holds open the original energizing circuit of relay 12 to prevent the reenergization or continued energization of relay 12 and thus prevents the allotter from allotting the same sender.

After the allotter has advanced one step it remains in this position until some other sender is to be allotted. If there has been a sender waiting allotment the energization of the relay corresponding to relay 12 at such sender supplies ground to the multiple starting conductor 15 which causes the advance of the allotter in a manner identical with that first described. Such a circuit can be completed as soon as relay 12 is deenergized upon the advance of the allotter, since such advance allows test relay 16 to be deenergized.

The sender is released in a manner substantially identical with that described in Patent No. 1,395,977. The continued deenergization of line relay 4 causes the deenergization of slow release relay 5 which causes the successive completion of self-interrupting circuits for magnets 6, 8, 10 and 11 of the control switch and the A, B, C registers respectively in a manner so obvious and well-known as not to need description. When the C register reaches its normal position register brush 14 opens the holding circuit of relay 13 and this relay is deenergized. The register relays of Fig. 3 are deenergized as soon as the battery supply is removed from the conductors to which said relays are locked through their right-hand windings. The release of these relays is accomplished in a manner identical with that described in Patent No. 1,395,977.

All parts of the apparatus have now been restored to their normal condition and are ready for reuse.

What is claimed is:

1. In a selection controlling system, a plurality of registering devices, a set of relays common thereto, a circuit, remote control means to position said registers, a plurality of outlets for said circuit provided by different settings of any one of said registering devices, and means to extend said circuit to a desired one of said outlets through contacts of a certain one of said relays.

2. In a selection controlling system, a plurality of registering devices, a set of relays common thereto, a circuit, remote control means to position said registers, a plurality of outlets for said circuit equal in number to the number of possible settings of any one of said registering devices, means to position a desired one of said registering

devices; and means to extend said circuit to a desired one of said outlets through contacts of one of said relays, and means operated in accordance with the setting of said registering device to determine to which outlet said circuit is to be extended.

3. In a selection controlling system, a plurality of sets of registering devices, a set of relays common to said registering devices, a circuit, remote control means to position said registers, a plurality of outlets for said circuit equal in number to the number of possible combinations of settings of any one of said sets of registering devices, and means to extend said circuit to a desired one of said outlets through contacts of certain ones of said relays.

4. In a selection controlling system, a plurality of registering devices, a set of relays common thereto, a circuit, remote control means to position said registers, a plurality of outlets for such circuit equal in number to the number of possible settings of any one of said registering devices, means to extend said circuit to a desired one of said outlets through contacts of a certain one of said relays, and means to determine with which registering device said relays are to be associated.

5. In a selection controlling system, a plurality of registering devices; a set of relays common thereto; a circuit, remote control means to position said registers, a plurality of outlets for such circuit equal in number to the number of possible settings of any one of said registering devices, means to extend said circuit to a desired one of

said outlets through contacts of a certain one of said relays, and an allotter switch to control the association of said relays with said registering devices.

6. In a selection controlling system, a plurality of registering devices, a set of relays common thereto, remote control means to position a desired one of said registering devices, means to associate said relays with a registering device which has been positioned, means to selectively energize said relays in accordance with the position assumed by said registering device, a circuit, a plurality of outlets for said circuit equal in number to the number of possible settings of said registering device, and means to extend said circuit to a desired one of said outlets through contacts of those relays which have been energized.

7. In a selection controlling system, a plurality of sets of registering devices, a set of relays common to said registering devices, a circuit, remote control means to position said registers, a plurality of outlets for said circuit equal in number to the number of possible combinations of settings of any one of said sets of registering devices; a magnet in circuit with each of said outlets, and means to extend said circuit to a desired one of said magnets through contacts of certain ones of said relays to record a registration equivalent to the joint setting of one of said sets of registering devices.

In witness whereof, I hereunto subscribe my name this 10th day of June A. D., 1922.

JOHN W. GOODERHAM.
